UNITED STATES PATENT OFFICE.

FAY M. HAYNES, OF ENCAMPMENT, WYOMING.

LOCK-JOINT FOR DRILLING-TOOLS.

1,355,144.

Specification of Letters Patent. Patented Oct. 12, 1920.

Application filed August 4, 1917. Serial No. 184,518.

To all whom it may concern:

Be it known that I, FAY M. HAYNES, a citizen of the United States, and resident of Encampment, in the county of Carbon and

5 State of Wyoming, have invented certain new and useful Improvements in Lock-Joints for Drilling-Tools, of which the following is a specification.

This invention relates to new and useful improvements in locking joints, and more particularly for lock joints especially adapted to be used on drilling tools, for connecting the drilling bits in a simple and efficient manner, and absolutely preventing the falling 10 of the bit from the connection and thus causing a great loss of time and labor. Unless the bit is securely connected, the same is liable to work loose, hence causing what is called "a fishing job", which is very laborious, and often delays the drilling operation for a considerable length of time. This type 15 of safety joints is formed with a head and socket, which are adapted to be engaged and partially rotated to coöperatively lock, and also is provided with additional locking 20 means, which is insertible when the first mentioned locking means is in operation.

Another object of the invention is to provide a device of this character which is 25 easily and simply constructed, inexpensive to manufacture, and one which will be very efficient in operation.

With these and numerous other objects in view, my invention consists of the novel features of construction, combination and arrangement of parts which will be herein referred to and more particularly pointed out in the specification and claim.

In the accompanying drawings—

40 Figure 1 is an elevation of the lock joint;

Fig. 2 is a vertical section through the same;

Fig. 3 is a horizontal section taken on the line 3—3 of Fig. 2; and

45 Fig. 4 is a horizontal section taken on the line 4—4 of Fig. 2.

Fig. 5 is a fragmentary perspective view showing the interlocking relation of the wings and rib portions of the lock joint.

50 In describing my invention I shall refer to the drawings in which similar reference characters designate corresponding parts throughout the several views.

The safety lock joint includes broadly a 55 head member 1, and a socket member 2, which are adapted to be coöperatively en-

gaged and interlocked in a manner to be hereinafter more fully described. The head member 1 is provided at its outer end with an internally threaded cone shaped socket 60 3, while the outer end of the socket member has a projecting cone shaped externally threaded portion 4, such parts being of the conventional type for connection in a drilling mechanism, as is readily apparent to 65 those skilled in the art. The head and socket members are provided adjacent their inner ends with flat sides 5 so as to facilitate relative rotation between the parts when they are assembled, for a purpose to be hereinafter more fully described. The socket member 2 adjacent its outer end is externally threaded as shown at 6 for a purpose to be hereinafter more fully described.

The head member 1 is provided with a 75 projecting rod 7 which extends from an annular enlarged portion 8 on the outer end thereof, and said rod 7 has formed on its other end a pair of projecting wings 9, at diametrically opposite points. The rod 7 is 80 provided between the enlarged portion 8, and wings with alining filler strips 10, which have their inner edges grooved as shown at 85 11 so as to loosely engage the adjacent portion of the rod 7.

The socket member 2 has formed therein an inner chamber 12 and this chamber adjacent to its open end has provided on diametrically opposite sides inwardly projecting rib portions 13 which are longitudinally 90 grooved as at 14 for accommodating the rod 7. The rib portions 13 are approximately the length of the filler strips 10, the latter being adapted to engage with said rib portions 13 to fill the space between them and to come 95 flush with the inner ends thereof when the rod 7 is inserted in the socket member and turned therein.

The socket member 2 is provided with a pair of elongated alining apertures or openings 15 therethrough, and the extremity of the rod 7 is likewise provided with a correspondingly shaped opening 16, said openings being adapted for alinement, when the various parts are correspondingly related, 105 for the insertion of a supplemental locking pin 17. To securely hold the locking pin 17 in position, a sleeve 18 is mounted on the socket member 2, said sleeve being internally threaded, and adapted to coöperatively engage the external threads 6 of said socket member, whereby the sleeve is adapt-

ed to be positioned over the ends of the pin 16, to securely hold the same in position, as clearly shown in Fig. 1 of the drawings, the sleeves being held from turning by 5 a set-screw 18'.

In operation when it is desired to connect a drill bit, the filling strips 10 are placed into position between the wings 9, and enlarged portion 8 and the rod 7, and 10 said projecting rod is inserted in the socket member 2. The filler strips 10 are adapted to take up all lost motion or side play of the rods 7 after the wings 9 pass through the oblong slot in the socket 2, it being 15 understood that the rod is turned one-quarter revolution in order to lock it in position, in which position the filler strips will take up side play while stationed between the top edges of the wings 9 and the 20 enlargement 8. Owing to the fact that the wings are adapted to slide between the inwardly projecting rib portions 13 of the chamber within said socket, it is obvious that the socket member and head member 25 are adapted to be slidably connected with each other. When the rod portion 7 has been inserted as far as possible within the socket member, the enlarged portion 8 thereof will be positioned in the open end 30 of the chamber in said socket member, as clearly shown in Fig. 2 of the drawings. When in this position, the members are partially rotated, whereupon the wings are positioned at right angles to the rib portion 13 in the passage within the socket member and thereby lock the rod 7 within 35 the socket member.

To additionally secure the members in locked position, when the first locking action 40 has taken place, as has been thus described, the alining openings 15 and 16 in the socket member and on the extremity of the rod 7 will aline, so as to permit a supplemental locking pin 17, to extend transversely therethrough. When the pin is in position, the 45 longitudinally adjustable sleeve 18 is moved down over the opposite ends thereof, to prevent accidental displacement of said pin, the sleeve being held from turning as specified. This double locking movement will securely hold the members together, and prevent any possibility of the drilling bit becoming disengaged.

From the foregoing, it is obvious that I 50 have provided a very simple and quickly attached and detached locking joint of this

character, that will be very efficient and durable in operation. The double locking operation, will absolutely prevent the drilling bit from working loose and hence causing the consequential loss in time and labor. To disconnect this joint, it is only necessary to remove the locking sleeve 18, disengage the pin 17, and rotate the head and socket members back to the first mentioned 60 position, whereby the projecting rod 7 may be easily withdrawn through the restricted passage in the outer end of the chamber 12 in said socket member.

From the above description taken in connection with the accompanying drawings, it is thought that a clear and comprehensive understanding of the construction, operation and advantages of my invention may be had, and while I have shown and described the device as embodying a specific structure, I desire that it be understood that such changes may be made in said structure as do not depart from the spirit and scope of the invention as claimed.

Having fully described my invention, what I claim as new, and desire to secure by Letters Patent is:—

A lock joint of the character described, comprising a head member having a reduced portion forming a rod and an enlargement concentrically of the rod at the inner end of the latter, wings formed on the rod at the outer end thereof, filler strips between the wings and the enlargement, a 85 socket member having a chamber for receiving the rod and wings, opposed rib portions formed in the chamber adjacent the open end thereof and adapted to receive therebetween the rod, whereby on the turning of the head member or the socket member the wings and rib portions will be interlocked with each other, said filler strips being 90 designed to fill the space between the rod and the wall of the chamber, said socket member and rod being formed with apertures adapted to register with each other on the interlocking of the wings and rib portions, a key removably fitted in the apertures when in registration with each other, and 95 a sleeve externally threaded on the socket member and adapted to move over the apertures therein for retaining the key in place.

In testimony whereof I affix my signature hereto.

FAY M. HAYNES.
